UNITED STATES PATENT OFFICE

WILLIAM SCHWALGE, OF ELMHURST, ILLINOIS

APPARATUS FOR RECLAIMING LUBRICATING OILS

Application filed June 26, 1930. Serial No. 483,986.

The invention relates to apparatus for reclaiming lubricating oils, and more particularly to apparatus for re-claiming or purifying lubricating oils that have been employed 5 in internal combustion engines, or the like.

Lubricants that have been employed in internal combustion engines, are, as a rule, diluted by gasoline, etc., and carry in suspension solids which discolor them.

- 10 One form of the invention is embodied in apparatus which comprises a housing into the lower end of which lubricant that is to be re-claimed is introduced under pressure, the construction being such that the lubricant 15 flows upwards in the housing through filtering material and thence into a receptacle filled with filtering material, and provided with a foraminous bottom wall which preferably rests on fibrous filtering material.
- 20 The fibrous filtering material is supported by a baffle plate positioned at the upper end of a tubular member having foraminous side walls.

The fibrous filtering material co-operates 25 with the baffle plate to distribute the lubricant substantially evenly at the top end of the tubular member so that it will gravitate downwards in small streams on the foraminous walls of the tubular member. Means 30 is provided for causing a flow of heated air through the foraminous walls to evaporate the gasolene in the small streams of lubricant flowing thereon, the temperature of the heated air being preferably less than the 35 flashpoint of the gasoline. The gasoline passes from the housing with the heated air. The purified lubricant is withdrawn from the bottom portion of the housing.

40 A feature of this invention is that the heated air is employed to heat the lubricant before and as it passes through the filtering material. This preheating of the lubricant combined with my improved method of dividing the lubricant into fine streams by evaporating 45 the gasoline insures that the apparatus will have a large capacity with respect to its size, but my invention is limited to this combination only to the extent indicated in the appended claims.

50 Many other objects and advantages will

appear as this description progresses, reference being had to the accompanying drawings, wherein:

Figure 1 is a side elevation of apparatus which embodies my invention;

Fig. 2 is a vertical central section taken through the improved apparatus shown in Fig. 1;

Fig. 3 is a section taken on line 3-3 of Fig. 2, and

Fig. 4 is a section taken on line 4-4 of Fig. 2.

Referring to the drawings, wherein I have illustrated a preferred embodiment of the invention, it will be noted that the apparatus 65 comprises a housing 10 which preferably consists of a bottom wall 11, a cylindrical side wall 12, and a removable top wall, or cap, 13, the cap 13 being provided with a flue 14. For convenience, the housing 10 is preferably 70 mounted upon a plurality of legs 15.

Disposed concentrically within the housing 10 and extending from the bottom wall 11 to adjacent the cap 13 is a cylindrical partition wall 17 which cooperates with the wall 12 75 to provide an annular chamber 18 extending from the bottom wall 11 to the upper end of the partition 17, the construction being such that the annular chamber 18 communicates with the flue 14.

80 A quantity of filtering material 20 is provided in the upper end of the annular chamber 18, the filtering material 20 being held between the wall 12 and the partition 17, and between foraminous annular members 22 and 23, the foraminous member 23 being preferably supported by angle irons 25 and 26 secured to the wall 12 and the partition 17, respectively. Any suitable filtering material, such as cotton-waste, mineral wool, or the 85 equivalent, may be used as the filtering material 20.

90 Lubricant which is to be re-claimed or purified is introduced into the chamber 18 through a pipe 28 communicating with the 95 lower end of the chamber, the pipe 28 being arranged to discharge lubricant in the chamber from a receptacle (not shown) positioned above the housing 10. This arrangement insures that the lubricant will flow into the 100

chamber 18 under pressure and will flow upwards therein through the filtering material 20 which removes solids held in suspension in the lubricant. The pipe 28 is preferably provided with a valve 29 so that the flow of lubricant to the housing may be interrupted when it is so desired.

Projecting through the upper end of the partition wall 18 at a point above the filtering material 22 is a pipe 30, whereby the lubricant may flow from the chamber 18 to be discharged in a receptacle 32 which preferably comprises a cylindrical wall 33 arranged concentrically within the partition wall 17. The receptacle 32 also comprises a foraminous bottom wall 34. It will be noted that the outer diameter of the cylindrical wall 33 is less than the inner diameter of the partition wall 17 so that an annular passage 35 is provided between these walls, which annular passage 35 communicates with the flue 14. The annular passage 35 extends downwards to the bottom wall 11, the lower end of which being formed between the partition wall 17 and a cylindrical foraminous tube 38 which extends from the bottom wall 11 to a point intermediate the top and bottom ends of the receptacle 32. Secured in the upper end of the foraminous tube 38, adjacent its upper end, is a baffle member 39 provided with an integral and downwardly and outwardly flaring flange 40. A quantity of filtering material 41 is supported by the baffle plate 39, which filtering material 41 is preferably fibrous for a purpose hereinafter set forth. The foraminous wall 34 of the receptacle 32 preferably rests upon the filtering material 41.

A quantity 43 of filtering material, preferably fuller's-earth, is supported by the foraminous bottom wall 34 and the filtering material 43 preferably supports, in turn, a quantity of filtering material 44 which preferably comprises cotton-waste, or the equivalent. It may be mentioned, that in some instances, I may omit the filtering material 43, or may employ other filtering materials in place of fuller's-earth at this point.

The filtering material 41 spaces the lower edge of the cylindrical wall 33 from the baffle plate 39 so that lubricant discharged into the receptacle 32 may flow through the filtering materials 44, 43 and 41 out on the flaring flange 40 and thence downwards on the foraminous tube 38. The fibrous material 41 co-operates with the baffle plate 39 to distribute the lubricant evenly on the top portion of the foraminous tubular member 38, and the foraminous tubular member 38 causes the lubricant to divide into extremely small streams. The gasoline, and water, in these fine streams is evaporated by air which flows through the interstices of the foraminous tube 38 and the heated air with the gasoline, water, etc., is discharged from the hous-

ing through the annular passage 35 and the flue 14.

The air is preferably heated to a temperature less than the flash temperature of the gasoline. In practice, I preferably heat the air to a temperature of approximately 235° F.

The purified lubricant collects at the bottom of the housing in an annular chamber formed between the inner surface of the partition wall 17 and the outer wall and the outer wall of a tubular member 45 which projects upwards from the bottom wall 11 and is based concentrically within the lower end of the foraminous tube 38. The lubricant may be withdrawn from the annular chamber through a pipe 46 which projects through the cylindrical wall 12 of the housing 10 and through the partition wall 17. The pipe 46 is preferably provided with a faucet 47, or the equivalent, at its lower end, which faucet may be adjusted to discharge the lubricant continuously from the apparatus, or may be opened from time to time when it is necessary to draw some of the purified lubricant from the housing.

I also preferably provide a vertically disposed overflow pipe 49 which projects through the bottom wall 11 and extends into the collecting chamber a distance less than the height of the tubular member 45.

A perforated tube 50 supported by the bottom wall 11 and of smaller diameter than the tubular member 45 is positioned concentrically with respect to the tubular member 45 and extends thereabove. The upper end of the perforated tube 50 is closed by an imperforate cap or baffle member 51 of relatively large diameter, the function of the baffle member 51 being to prevent lubricant, etc. from flowing into the tube 50 through the perforations therein. The tube 50 houses an electrical heating element 53 which is supported upon the bottom wall 11, the bottom wall 11 being provided with perforations 54 within the area defined by the tube 50 so that air may flow upwards into the tube 50 past the heating element 53, and thence through the perforations in the tubes 50 and 38 to the annular passage 35 which communicates with the flue 14.

The foraminous tube 38 may be made of any suitable material. Thus, I have shown it constructed of sheet metal which is provided with numerous small perforations. However, I contemplate constructing the foraminous tube 38 of a wire mesh, in some instances.

Pet-cocks 56 and 57 secured to the bottom wall 11 communicate with the collecting chamber and with the annular chamber 18, respectively, to permit withdrawal of lubricant from these chambers when it is so desired.

It will be noted that the tubular member

45 prevents the heating element 53 from directly heating the lower ends of the foraminous tube 38 and the partition wall 17 so that these parts will not be heated to an undesirable temperature. However, the air heated by the heating element 53 heats the lubricant flowing in the annular chamber 18 by conduction through the partition wall 17, it being readily understood that the filtering materials in the annular chamber 18 and in the receptacle 32 are also heated in a like manner. This arrangement causes some of the gasoline, etc. to evaporate before the lubricant passes through the receptacle 32, the gasoline, etc. thus evaporated being carried off through the flue 14 by the heated air.

While I have shown and described certain embodiments of my invention it is to be understood that it is capable of many modifications. Changes, therefore, in the construction and arrangement may be made without departing from the spirit and scope of the invention as disclosed in the appended claims, in which it is my intention to claim 25 all novelty inherent in my invention as broadly as possible in view of the prior art. What I claim as new, and desire to secure by Letters Patent, is:

1. Apparatus of the kind described comprising filtering means, a foraminous member disposed beneath said filtering means and adapted to receive oil flowing therefrom, and means for heating said oil as it flows over said foraminous member.

2. Apparatus of the kind described comprising filtering means, a foraminous member disposed beneath said filtering means and adapted to receive oil flowing therefrom, and means for causing a flow of heated air 40 through said foraminous member.

3. Apparatus of the kind described comprising a housing, a partition wall in said housing, said partition and said housing forming a chamber therebetween, means for introducing waste lubricating oil into the bottom end of said chamber, filtering means disposed in said chamber, foraminous means over which oil flows after passing through said filtering means, and means for causing a flow of heated air over said foraminous means.

4. Apparatus of the kind described comprising a housing, a partition wall in said housing, said partition and said housing forming a chamber therebetween, means for introducing waste lubricating oil into the bottom end of said chamber, filtering means disposed in said chamber, foraminous means over which oil flows after passing through said filtering means, and means for causing a flow of heated air through said foraminous means.

5. Apparatus of the kind described comprising a receptacle having a foraminous bottom wall, filtering material in said re-

ceptacle, a foraminous member forming an enclosure extending below said receptacles, a baffle plate in said foraminous member, filtering material supported by said baffle plate, said last-mentioned filtering material supporting said foraminous bottom wall, and means for causing a flow of heated air through said foraminous member.

6. Apparatus of the kind described comprising a housing, a tubular partition wall positioned in said housing and co-operating therewith to form an annular chamber, means for introducing waste lubricating oil into the lower end of said chamber, a tubular annular foraminous member positioned within said tubular partition wall, and means for causing a flow of heated air through said tubular foraminous member.

7. Apparatus of the kind described comprising a housing, a tubular partition wall positioned in said housing and co-operating therewith to form an annular chamber, means for introducing waste lubricating oil into the lower end of said chamber, filtering means in said chamber, a tubular annular foraminous member positioned within said tubular partition wall, and means for causing a flow of heated air through said tubular foraminous member.

8. Apparatus of the kind described comprising a housing, a tubular partition wall in said housing, said partition wall co-operating with said housing to form an annular chamber, means for introducing waste lubricating oil into said chamber, a tubular foraminous member positioned within said tubular partition wall and cooperating therewith to form an annular passage, and means for causing a flow of heated air through said annular passage.

9. Apparatus of the kind described comprising a housing, a tubular partition wall positioned in said housing and cooperating therewith to form an annular chamber, means for introducing lubricating oil into said chamber, a receptacle positioned within said tubular partition wall and provided with a foraminous bottom, filtering material in said receptacle, a tubular foraminous member extending below said receptacle, and heating means for causing a flow of heated air through said foraminous member.

10. Apparatus of the kind described comprising a housing having a perforated bottom wall, a tubular partition wall positioned in said housing and cooperating therewith to form an annular chamber, means for introducing waste lubricating oil into the lower end of said chamber, filtering material in said chamber, a receptacle positioned within said tubular partition wall and provided with a foraminous portion, filtering material in said receptacle, a tubular foraminous member extending below said receptacle, heating means, and perforated means enclosing said

heating means, said perforated means being disposed within said tubular foraminous member.

11. Apparatus of the kind described comprising a vertically disposed foraminous member forming an enclosure, means surrounding said foraminous member and cooperating therewith to form a stack through which gases may escape from the apparatus, a perforated member disposed within said foraminous member, means disposed within said perforated member for heating air which passes through said perforated member and said foraminous member to said stack, and means for delivering oil to said foraminous member.

12. Apparatus of the kind described comprising a vertically disposed foraminous member forming an enclosure, means surrounding said foraminous member and cooperating therewith to form a stack through which gases may escape from the apparatus, a perforated member disposed within said foraminous member, means disposed within said perforated member for heating air which passes through said perforated member, and filtering means for delivering oil to said foraminous member.

13. Apparatus of the kind described comprising a vertically disposed foraminous member forming an enclosure, means surrounding said foraminous member and cooperating therewith to form a stack through which gases may escape from the apparatus, a perforated member disposed within said foraminous member, means disposed within said perforated member for heating air which passes through said perforated member, means for delivering oil to said foraminous member, and an over-flow tube disposed within said foraminous member.

In testimony whereof, I hereunto affix my signature, this 10th day of June, 1930.
